UNITED STATES PATENT OFFICE.

JOSEPH S. PFREMMER, OF FOUNTAIN, MINNESOTA.

TRACTION-ENGINE.

SPECIFICATION forming part of Letters Patent No. 706,685, dated August 12, 1902.

Application filed April 28, 1902. Serial No. 105,100. (No model.)

To all whom it may concern:

Be it known that I, JOSEPH S. PFREMMER, a citizen of the United States, residing at Fountain, in the county of Fillmore and State 5 of Minnesota, have invented certain new and useful Improvements in Traction-Engines; and I do declare the following to be a full, clear, and exact description of the invention, such as will enable others skilled in the art to 10

to which it appertains to make and use the same.

The invention relates to traction-engines.

The object of the invention is to provide a traction-engine the boiler of which is capable of vertical adjustment at one end, whereby 15 it may be maintained in a true horizontal position while the engine is in the act of either ascending or descending a hill, thus equally distributing the water throughout the entire length of the boiler.

20 With the above and other objects in view, which will readily appear as the nature of the invention is better understood, said invention consists in certain novel features of construction and combination and arrangement of parts, which will be hereinafter fully described, defined in the appended claims, and illustrated in the accompanying drawings, in which—

Figure 1 is a side elevation of a traction-30 engine illustrating my invention. Fig. 2 is a similar view of the forward end of the engine, taken from the opposite side to that shown in Fig. 1. Fig. 3 is a front end view. Fig. 4 is a detail perspective view of the axle-block, the forward end of the reach, and a fragment of the axle. Fig. 5 is an end view of the same and a fragment of the axle. Fig. 35 6 is a cross-sectional view through the line $x-x$ of Fig. 1. Fig. 7 is a view of the clutch.

40 In the drawings, 1 denotes the boiler of a traction-engine; 2, the traction-wheels; 3, the front steering-wheels, and 4 the front axle, to which the steering-wheels are journaled.

45 5 denotes guideways secured to the opposite sides of the boiler near its forward end in any suitable manner—as, for instance, by brackets 5', which may be formed at the opposite ends of said guideways and which are 50 bolted or riveted to the sides of the boiler or are connected in any other suitable manner.

6 denotes a supporting-frame, preferably

in the form of a yoke, the vertical members 7 of which have a dovetail connection with the guideways 5 to permit of the raising and 55 lowering of the forward ends of the boiler in a manner presently to appear. The lower end 8 of this frame is provided with a longitudinal guideway 9, of dovetail construction, adapted to engage a block 10, preferably of 60 dovetail construction. This block 10 is secured to a bail portion 11, and between the bail portion 11 and the block 10 extends the axle 4. A king-bolt 12 passes through the block 10, axle 4, and bail 11 and is provided 65 with the usual clamping-nut 13. 12' denotes a reach, the forward end of which is hinged to the block 10 and the rear end to a fixed part of the traction-engine—as, for instance, 70 the boiler fire-box.

In raising or lowering the forward end of the boiler it describes the arc of a circle whose center is coincident with the rear axle 14 of the engine. Hence there must be a relative movement between the axle 4 and the 75 frame 6 to permit of the raising and lowering of the forward end of the boiler. By connecting the frame 6 to the axle in the manner just described such movement is permitted.

15 denotes the power-shaft of the engine, 80 and 16 denotes a counter-shaft, each shaft being journaled in suitable bearings attached to the shell of the boiler. 17 denotes a gear-wheel loosely mounted on said shaft 15, and 18 denotes a clutch of any suitable form and 85 construction, also mounted on said shaft, the construction being such as to permit of the locking of the gear-wheel to said shaft to rotate therewith.

19 denotes an operating-lever, and 20 denotes a link connecting said lever to the clutch.

21 denotes a crank-wheel fixed to one end of the shaft 16, and 22 denotes a crank-arm fixed to the opposite end of the shaft 16. 95

23 denotes a gear-wheel, preferably of the worm type. This gear-wheel may be formed integral with or on the periphery of the crank-wheel 21 and is engaged by a worm 24, fixed to a shaft 25, journaled in bearings 26 and 100 having a gear-wheel 27 in mesh with the gear-wheel 17.

28 denotes a link, the upper end of which is connected to a wrist-pin 29, projecting from

the face of the crank-wheel, and the lower end of which is pivoted to one of the arms 7 of the supporting-frame 6. A similar link 30 is connected to the crank 22 and to the other 5 arm 7 of the frame 6 on the opposite side of the machine.

In operation, assuming the traction-engine to be traveling upgrade and it be desired to maintain the boiler in a true horizontal position, the lever 19 is operated to fix the gear 17 to the shaft 15, thus causing said gear to rotate said shaft and through the intermediate gearing to impart a rotary movement to the crank-wheel 21 and crank-arm 22. Assuming the parts to be in the position shown in Fig. 1 and the crank-wheel to be rotating in the direction of the arrow indicated thereon, the forward end of the boiler will be lowered, and when it reaches a true horizontal position the 10 lever 19 is operated to disengage the gear 17 from the wheel 27 and the worm 24 will lock the worm-wheel 23 from rotation, and thus hold the boiler in a true horizontal position. When the engine reaches a horizontal grade, 15 it of course will be necessary to lower its forward end, so as to make the boiler parallel with the grade. The lever 19 is again operated to set the crank-wheel in motion, and this wheel rotating in the same direction will 20 at the instant it carries its crank-pin 29 past a vertical line drawn through the axis of the wheel begin to elevate the forward end of the boiler until the boiler is in the true horizontal position and the crank-pin is at a point 25 directly opposite the position shown in Fig. 1 of the drawings. The engine is now traveling upon a level road; but supposing a down-grade is encountered the wheel 21 is again set in motion and rotates in the same direction, 30 and at the instant the crank-pin 29 passes a line drawn horizontally through the axis of the wheel the forward end of the boiler will be elevated. The crank-wheel is free to make 35 a complete rotation, and when the crank-pin thereof is at its highest point of rotation the forward end of the boiler is at its lowest point of adjustment. When the crank-pin is at its 40 lowest point of rotation, the forward end of the boiler is at its highest point of adjustment, and when the crank-pin is upon either 45 side of a line drawn vertically through the axis of the crank-wheel and is equidistant between the highest and lowest point of the crank-wheel the boiler is in a true horizontal 50 position.

From the foregoing description, taken in connection with the accompanying drawings, it is thought that the construction, mode of operation, and advantages of my improved 55 traction-engine will be readily apparent without requiring a more extended explanation.

Various changes in the form, proportion, and the minor details of construction may be resorted to without departing from the principle or sacrificing any of the advantages of 65 this invention.

Having thus described my invention, what I claim as new, and desire to secure by Letters Patent, is—

1. In a traction-engine, the combination 70 with a boiler and the front axle and wheels journaled thereon; of a supporting-frame having a longitudinal sliding engagement with the axle and a sliding engagement with the boiler, and means for vertically adjusting 75 the boiler with respect to the supporting-frame.

2. In a traction-engine, the combination with the boiler, its traction-wheels and the forward supporting-wheels and their axle; of 80 a frame having a longitudinal sliding connection with said axle, said boiler having a vertically-adjustable connection with said supporting-frame, and means for adjusting said boiler. 85

3. In a traction-engine, the combination with a boiler and its traction-wheels and its forward supporting-wheels and their axle, a frame connected to said axle and having vertical standards, guides fixed to the sides of 90 the said boiler and engaging said standards, a shaft journaled to said boiler, cranks connected to said shaft, links connecting said cranks to the vertical members of the supporting-frame, a worm-wheel mounted to turn with 95 said shaft, a worm in mesh with said wheel, and means for rotating said worm.

4. In a traction-engine, the combination with a boiler, its traction-wheels and its forward supporting or steering wheels and their 100 axle, a frame connected to the axle and having vertically-disposed members, guideways secured to the sides of the boiler and having a dovetailed sliding connection with said vertical members, a shaft extending across the 105 boiler and provided at one end with a crank and at the other end with a crank-wheel having formed thereon or made integral therewith a worm-wheel, links, one connecting the crank-wheel with one of said vertical members and the other connecting the crank with the other vertical member, a worm in engagement with the worm-wheel, and means for rotating the worm. 110

In testimony whereof I have hereunto set 115 my hand in presence of two subscribing witnesses.

JOSEPH S. PFREMMER.
